UNITED STATES PATENT OFFICE.

WELLINGTON H. KIDDER, OF ROOSEVELT, NEW YORK, ASSIGNEE, BY MESNE ASSIGNMENTS, TO UNDERWOOD COMPUTING MACHINE COMPANY, OF NEW YORK, N. Y., A CORPORATION OF NEW YORK.

STAND OR SUPPORT FOR LOOSE-LEAF BOOKS, &c.

1,278,678.

Specification of Letters Patent. Patented Sept. 10, 1918.

Application filed February 20, 1915. Serial No. 9,524.

To all whom it may concern:

Be it known that I, WELLINGTON H. KIDDER, a citizen of the United States, residing in Roosevelt, Long Island, in the county of 5 Nassau and State of New York, have invented certain new and useful Improvements in Stands or Supports for Loose-Leaf Books, &c., of which the following is a specification.

10 This invention relates to devices of the general nature of copy holders, and is hereinafter disclosed as an improvement on my co-pending application No. 871,229, filed November 10, 1914, wherein a stand for an 15 Underwood Standard adding machine is shown as having a table leaf adapted to support work, and a book rack adapted to hold a loose-leaf book.

It is extremely desirable, especially in a 20 crowded office, to have the machine take up as little room as possible when not in use. This could be done by providing the stand with work supporting devices which could be lifted bodily from the stand; but in such 25 a device the leaves of the book may be misplaced or broken or soiled, which would cause a great deal of trouble and loss of time. In order to overcome these disadvantages, I attach the work supporting devices to the stand in such a way as to be out 30 of the way when not in use, but still being attached to the stand. I may also provide means whereby the loose-leaf book rack may be brought into position for use without 35 bringing the work supporting leaf into position for use.

In bringing about these and other advantages, I find it advantageous to mount the book-rack so that it will swing on the 40 stand. The work supporting table leaf may be mounted to swing on the book-rack from a horizontal position when in use to a dependent position when not in use, while a bracket mounted to swing on another part 45 of the stand may support the leaf in its horizontal position. The parts thus mounted may fold together so that they occupy very little room.

Other features and advantages will hereinafter appear.

In the accompanying drawings,

Figure 1 is a front elevation of a stand for an Underwood Standard typewriting

and adding machine, showing the work supporting devices in their extended positions. 55

Fig. 2 is a fragmentary elevation of the loose-leaf book rack, showing the position the book assumes when placed in said rack.

Fig. 3 is a fragmentary perspective view of the machine on the stand, showing the 60 relative position of the work supporting devices when extended for use.

Fig. 4 is a perspective view of the work supporting devices when folded together, showing part of the machine and stand. 65

Fig. 5 is a side elevation of the work supporting devices showing part of the stand, and showing the relative position of the parts when the loose-leaf book rack is being used alone. 70

The stand upon which is mounted a typewriting and adding machine, comprises a top portion 1, legs or supports 2, and horizontal brace rods 3 connecting the legs. The forward left-hand leg of the stand is provided with a lug 4 fast near the top thereof. Pivoted to this lug 4 and bearing upon the upper face thereof is an extension 5 forming part of a loose-leaf book rack. 75

The book rack or container comprises a rectangular frame 6 formed by a metal strip, and U-shaped brackets 7 secured to the frame 6 and supported beneath the opening of the said frame 6. Rests 8 secured in the bottom of the U-shaped 85 brackets 7 are adapted to receive the back of the book when passed through said open portion of the frame 6; thus the frame 6 and the rests 8 form a pocket which will hold the book partly open while resting with its covers against the two long walls of the opening in the rectangular frame 6. The pocket converges downwardly, due to the fact that the width of the opening in the frame 6 is greater than the thickness of the 90 back binding of the book. 95

The front left-hand leg of the stand is provided with a lug 9 fast thereto near the horizontal braces 3. Pivoted to this lug 9 is a brace 10, which extends upwardly and is fast to the outer side of the frame 6, and assists the extension 5 to support the book rack 6 in a horizontal position. The book rack and its brace 10 are pivotally mounted on the stand so that they may be swung in 100 close against the side of the machine, (as

shown in Fig. 4) when out of use. In this position the rack will still accommodate a book, thus keeping the book near the machine as is convenient, especially when the book is used a great many times at short intervals.

The work supporting device is provided with a table leaf 11 which may be swung into usable position adjacent the book rack.

10 when the book rack is in extended position. The table leaf 11 is connected to the rear side of the frame 6 of the book rack by hinges 12 having pintles 13 fast to the leaf 11 bearing in the knuckles 14 fast to the

15 frame 6 of the book rack.

The table leaf 11 is held up and supported in a horizontal position by a horizontally swinging bracket 15, which the operator swings into position when the leaf 20 has been raised. This bracket 15 is provided with a horizontal arm 16 upon which the table bears, and a brace 17 which supports the outer end of the arm 16. The bracket 15 is mounted to swing on the stand 25 by means of an upper lug 18, and a lower lug 19 fast on the rear left hand leg 2 of the stand. The arm 16 of the bracket swings on a pin 21 on the upper lug 18, while the brace 17 of the bracket bears on a 30 pivot on the lower lug 19. The arm 16 of the bracket has fast thereon metal clamps 20 bellied out so as to receive and clamp resilient plugs 22 adapted to support the leaf 11 and so protect the table against being scratched when the bracket 15 is supporting said table leaf.

In order to bring the parts into position for use, assuming that they occupy the position shown in Fig. 4, the operator simply 40 takes hold of the frame 6 and swings it forward; whereby the book rack is brought into position for use. If the operator desires to use the leaf 11 in addition to the book rack, said leaf 11 is lifted to horizontal 45 position and held there until the bracket 15 is swung to a position near the rear side of the leaf 11. The bracket 15 is prevented from swinging too far by the position of the lugs 18 and 19 which cause the 50 arm 16 and brace 17 to abut against the leg of the stand when swung out to proper position to hold the leaf 11. By returning the bracket 15 to its position close to the stand, and allowing the leaf 11 to drop to its vertical 55 position, the book rack may be swung close to the machine stand as shown in Fig. 4; the parts will be out of the way but still accessible to the operator at a moment's notice. It will be seen that when the parts 60 are in this position, the leaf 11 will have its work face toward the stand, thus being protected against being scratched or marred.

The stand also includes the work supporting leaf 23 which may be pivoted on 65 the other side of the stand in any desired

manner. This leaf 23 is mounted entirely independent of the book rack or supporting leaf 11, and may be used with or without the described devices, but forms a convenient support for a work sheet at the right 70 hand of the operative.

Variations may be resorted to within the scope of the invention, and portions of the improvements may be used without others.

Having thus described my invention, I 75 claim:

1. The combination with a work-stand, of a container mounted thereon to swing about a vertical axis from a position in which it projects outwardly from the stand to a folded position in which it lies along the stand, a leaf mounted on said container to swing downwardly from a work-holding position to a pendent position while the container is in said outwardly projecting position, and to swing with the container to a position lying between the container and the stand as the latter moves to said folded position, and disengageable means for supporting said leaf when in its work-holding position. 80 85 90

2. The combination with a work-stand, of a container mounted thereon to swing about a vertical axis from a position in which it projects outwardly from the stand to a folded position in which it lies along the stand, 95 a leaf mounted on said container to swing downwardly from a work-holding position to a pendent position while the container is in said outwardly projecting position, and to swing with the container to a position lying between the container and the stand as the latter moves to said folded position, and a bracket projecting from the stand beneath the leaf to support it in said work-holding position, said bracket mounted on the stand 100 to swing to a folded position between the stand and the leaf as the leaf and container are folded to the stand. 105

3. The combination with a work-stand, of a container mounted thereon to swing about a vertical axis from a position in which it projects outwardly from the stand to a folded position in which it lies along the stand, a work-holding leaf hinged to said container to swing downward from a horizontal or work-supporting position to a pendent position, and to lie folded with said container along the side of said stand, and disengageable means for supporting said leaf when in its work-supporting position, 110 115 120 said work-holding leaf when in its work-supporting position constituting means for preventing movement of said container to its folded position.

4. The combination with a work-stand, of a container mounted thereon to swing about a vertical axis from a position in which it projects outwardly from the stand to a folded position in which it lies along the stand, a work-holding leaf hinged to said container to 125 130

- tainer to swing downward from a horizontal or work-supporting position to a pendent position in which it may be swung with said container to its folded position along the 5 side of the stand, and a supporting bracket for said leaf hinged to the stand to swing from a projecting position in which it underlies and supports the leaf to a folded position at the side of the stand, permitting the 10 leaf to be swung down and to its folded position, said supporting bracket and leaf, when in work-supporting position, constituting means tending to prevent the leaf and container from swinging in one direction.
- 15 5. The combination with a work-stand, of a work-holder and a work-supporting leaf, and means for mounting said holder and leaf in work-holding position adjacent to each other and extending outwardly from a side 20 of said stand so as to be accessible for use from its front, said mounting means including hinged connections to permit said holder and leaf to be swung to a folded position along the side of said stand, with the holder 25 still accessible for use from the front, but with the leaf folded out of the way between the holder and the stand.
6. The combination with a work-stand, of a support mounted on the stand near a front 30 corner thereof to project outwardly from the stand, a work-supporting leaf extending rearwardly from the support in a horizontal work-holding position at the side of the stand, said leaf hinged to the support to 35 swing downward and forward to a pendent position, and means for sustaining said leaf when in work-holding position but disengageable to permit said leaf to be swung to its pendent position, the support being 40 hinged to swing about a vertical axis while the leaf is pendent, to bring leaf and support to a folded position at the side of the stand, with the work-supporting surface of the leaf facing the stand and protected 45 thereby, said support comprising an open top work-container.
7. The combination with a work-stand, of
- a container mounted thereon to swing about a vertical axis from a position in which it projects outwardly from the stand to a folded position in which it lies along the stand, a work-holding leaf hinged to said container to swing downwardly from a horizontal or work-supporting position to a pendent position in which it may be swung 55 with said container to its folded position along the side of the stand, and a supporting bracket for said leaf hinged to the stand to swing from a projecting position in which it underlies and supports the leaf to a folded 60 position at the side of the stand, permitting the leaf to be swung down and to its folded position, said leaf when in its work-supporting position constituting means for preventing movement of said container to its folded 65 position, and said supporting bracket and leaf, when in work-supporting position, constituting means tending to prevent the leaf and container from swinging in the opposite direction. 70
8. The combination with a work-stand, of a container mounted to project outwardly from one side of said stand, a work-supporting leaf mounted at the same side of said stand adjacent to said container, and detachable means for supporting said leaf in its work-supporting position, the mounting for the leaf and container including means for shifting said leaf and container to a second position with the container lying along the 75 side of said stand, and the leaf in a pendent position between the stand and the container, the container and leaf being accessible for use by an operator working at the stand when the parts are in their first-mentioned 80 position, and the container being still accessible for use by an operator working at the stand when the parts are in their second-mentioned position. 85
